John Anderson,

UNITED STATES PATENT OFFICE

HENRY H. LAMPERT, OF CHICAGO, ILLINOIS

FORM CLAMP

Application filed April 23, 1928. Serial No. 272,108.

The main objects of this invention are to provide an improved form of mold construction particularly adapted for use in the construction of concrete beams; to provide an improved form of clamp for supporting the mold sections and for detachably securing the wall sections to the soffit section; to provide a mold clamp having improved means for attachment to a form tie; and to provide an improved clamp of this kind which is adjustable so as to be adapted to accommodate molds of different sizes.

An illustrative embodiment of this invention is shown in the accompanying drawing, 15 in which:—

Figure 1 is a transverse vertical section of a beam mold showing improved supporting and clamping means applied thereto.

Fig. 2 is a bottom plan of the same. 20 Fig. 3 is a top plan of the same, on a reduced scale.

Fig. 4 is a detail in perspective of the clamping means.

In the form shown, the improved clamp is 25 applied to a mold comprising a soffit section 1 and a pair of side wall sections 2.

The soffit section 1 is spaced from the bottom of a structural shape 3 by a plurality of spacers 4 having prongs 5 which are driven 30 into the soffit.

The wall sections 2 are usually made of planks strengthened by spaced upright cleats 6.

In the construction shown, the improved 35 clamp comprises a beam 7 and a pair of jaws 8 adjustably mounted thereon in position to embrace the lower part of the mold.

The beam 7 preferably comprises a channel iron including a web 9 and depending 40 flanges 10. The web 9 forms a supporting shelf for the mold and is provided with a plurality of transversely disposed spaced slots 11 formed therein for receiving the bight of a form tie 12.

45 The form tie 12 is arranged to form a supporting sling having its bight looped around a portion of the beam 7. The tie 12 extends between the wall sections 6 and the edges of the soffit 1 or, if desired, it may pass through 50 apertures, not shown, formed in the soffit sec-

tion. The ends of the tie band are secured to the structural shape 3 by clamps 13.

The channel beam 7 may be temporarily fastened to the soffit section 1 by nails 14 extending through certain of the slots 11. 55

In the construction shown, the jaws 8 comprise channel bars having webs 15 and flanges 16. Formed in the webs 15, are slots 17 for receiving fastening bolts 18 provided with wing nuts 19. 60

The bolts 18 may be seated in any of the slots 11 for adjustably securing the jaws 8 to the beam 7. The jaws 8 may thereby be moved toward and away from each other for accommodating molds of different sizes. 65

If the jaw 8 is directly opposite a cleat 6, the jaw is shifted inwardly to bring its inner flange 16 into engagement with the cleat as shown at the right of Fig. 1. If the jaw is not opposite a cleat, a kicker strip 20 is 70 placed between the cleats 6 and the jaw, as shown at the left of Fig. 1.

In operation, the beam 7 is nailed to the bottom of the soffit section and the tie element 12 is then looped around the soffit 1 and a 75 portion of the beam 7. The slots 11 permit the clamp to accommodate soffits of different widths.

After the tie band has been secured to the structural shape 3, the wall sections 2 are 80 placed on the beam 7 and detachably secured to the soffit 1 by the jaws 8.

Although but one specific embodiment of this invention has been herein shown and described, it will be understood that numerous 85 details of the construction shown may be altered or omitted without departing from the spirit of this invention as defined by the following claims.

I claim:

1. In a device of the class described, a clamp comprising a channel-shaped beam adapted to support mold sections and having a plurality of apertures formed in the web thereof at substantially regular intervals, 95 a form tie arranged to form a supporting sling having its bight looped around a portion of said beam within the channel and extending through certain of said apertures, a pair of jaws supported on said beam for en- 100

gaging the mold sections, and a bolt seated in one of the other apertures for adjustably securing one of said jaws to said beam.

2. In a device of the class described, a clamp comprising a channel shaped beam adapted to support mold sections and having a plurality of apertures formed in the web thereof and spaced apart longitudinally thereof for receiving a form tie, a pair of jaws supported on the web of said beam for engaging the mold sections, and a pair of bolts seated in two of said apertures for adjustably securing said jaws to said beam, the heads of said bolts being located within the channel.

Signed at Chicago this 20th day of April 1928.

HENRY H. LAMPERT.
